UNITED STATES PATENT OFFICE.

TIMOTHY H. PETTENGILL, OF AMSTERDAM, NEW YORK.

TURBINE.

Application filed November 9, 1918. Serial No. 261,813.

To all whom it may concern:

Be it known that I, TIMOTHY H. PETTENGILL, a citizen of the United States, residing at Amsterdam, in the county of Montgomery and State of New York, have invented certain new and useful Improvements in Turbines, of which the following is a specification.

My invention relates to an elastic fluid 10 turbine of the impact type, driven by the energy of jets of elastic fluid acting upon movable vanes.

One object of the invention is to provide a simple turbine of high efficiency which can 15 be constructed at a low cost.

Another object of this invention is to devise a steam turbine which will have the efficiency of the modern turbines now in commercial use and at the same time one which 20 can be constructed at a much lower cost.

The invention is very simple, consisting merely of one or more sets of movable vanes mounted on a rotating element and passages or nozzles carried by the casing through 25 which the elastic fluid flows and is discharged against the vanes at predetermined intervals in its course around the rotating element.

The steam passages or nozzles are so constructed that the jets of elastic fluid are 30 charged in the direction of rotation. Each nozzle or passage extends parallel with the sets of vanes, the passages being entirely open on the side next to the vanes, the outer wall of the passage being parallel to the 35 vanes for a considerable distance, finally converging at its outer end toward the vanes. As the elastic fluid bursts forward in the direction of rotation from its confinement through the nozzle, the side of the jet 40 is shaved off, as it were, in passing the edges of the movable vanes due to the broadening of the jet on leaving the nozzle, a small portion of the jet being caught by each vane in passing, until the complete energy of the jet 45 is absorbed, the energy of each jet being distributed over a large number of vanes.

This arrangement requires very simple mechanical means and at the same time is effective in extracting the maximum energy 50 from the jets which are free to burst into maximum velocity on account of the flow of the fluid not being clogged by any back pressure, due to limited vane openings.

The primary nozzles are arranged in parallel in alignment transversely of the turbine, with the succeeding nozzles, which are

in series with the primary nozzles, following consecutively in the direction of rotation, in circumferential alignment.

Each nozzle is connected with the steam 60 chest by a valve which is under the control of the governor and the number of nozzles should be limited to a number just sufficient for good speed regulation. In other words, the fewer nozzles used, the greater will be 65 the number of vane openings which each can cover. The number of vane openings which should be covered by each nozzle in proportion to the cross sectional area of same and the number of nozzles to be arranged in series for maximum efficiency can best be determined by experiment.

In the accompanying drawings Fig. 1, is a sectional view of one half of a turbine embodying my invention, taken on the line 2—2 of Fig. 2.

Fig. 2, is a sectional view in detail laid out flat, illustrating the arrangement of nozzles.

Fig. 3, is a view showing one of the metal 80 pieces which are attached to the casing to form the nozzles.

Fig. 4 is an enlarged diagram which gives a better idea of the principle of the parallel nozzles than can be shown in Fig. 2.

Referring now to Figs. 1 and 2, the movable vanes A, of which there may be any number of rows, are mounted on the rotating element or wheel M, and the parallel nozzles H, and adjacent chambers H' are 90 formed by the outside rims B, and the metal pieces b, shown in Fig. 3, which are bolted to the casing K.

The steam or elastic fluid enters at E, Figure 2, and is delivered to the movable 95 vanes through the parallel nozzles H. The elastic fluid from the several inlets merge together after passing through the first nozzles of the series. The succeeding nozzles are made successively larger and longer 100 toward the exhaust to take care of expansion and at the end of the series may occupy the entire space between the movable vanes, the fluid finally exhausting through outlets O.

This arrangement makes a very compact machine and economizes on cost of construction. It also increases the efficiency when part of the inlet valves are closed by the governor and the turbine is running on 110 light load as the degree of expansion is increased on the remaining primary jets

left working, they having the full area of the machine for expansion.

As all of the rows of movable vanes are mounted on one rotating element or wheel 5 and the jets from the several primary nozzles merge together after passing through the first nozzles and the flow of elastic fluid is around the rotating element, liberal clearance can be allowed without a waste of elastic fluid, due to leakage, as the leakage is 10 toward the exhaust and is caught by the succeeding receiving chambers D.

Fig. 4, is an enlarged diagram showing the arrangement of nozzles similar to Fig. 15 2, except that only two rows of vanes are shown and there is an inlet for each primary nozzle. As the elastic fluid bursts forward 20 in the direction of rotation from its confinement at H' through nozzle H, the side of the jet is shaved, as it were, as illustrated by arrows, in passing the edges of the movable vanes A, due to the jet of fluid broadening on leaving the nozzle. The fluid is allowed to seek its own angle in 25 striking the edges of the vanes, a small portion of the jet being caught by each vane in passing until the complete energy of the jet is absorbed.

The forward flow of the high velocity 30 fluid is stopped abruptly on entering the vane openings, and such a small quantity is caught by each vane that it leaves the vanes at comparatively low velocity, due to the ample opening of the vane compared 35 to the small quantity of high velocity fluid shaved from the jet in passing the edge of

the vane, and is ejected from the vanes at a low velocity due to the area of the vane opening far exceeding the area of the nozzle opening.

The length of the nozzles is shortened in Fig. 2, merely to save room to illustrate that the nozzles are made successively larger toward the exhaust and at the end of the series may, if desired, occupy the entire 45 space between the movable vanes.

I claim:

An elastic fluid turbine comprising a rotary drum, a plurality of spaced vanes carried thereby, a casing surrounding the drum, 50 inlet chambers arranged between the sets of vanes, the chambers between alternate sets of vanes being aligned transversely of the drum and in staggered relation with the other alternate aligned chambers forming a plurality of staggered sets of chambers, nozzles leading from the alternate chambers and overlapping the adjacent alternate chambers on the opposite side of the vanes, said nozzles lying parallel with 55 the rotation of the vanes and open on one side whereby the fluid from one set of alternate aligned chambers is directed laterally through the vanes to the other set of alternate aligned chambers, said nozzles and chambers increasing proportionately in 60 length toward the exhaust end of the turbine.

In testimony whereof I affix my signature.

TIMOTHY H. PETTENGILL.
